UNITED STATES PATENT OFFICE.

HUGH CHRISTIE, OF BOSTON, MASSACHUSETTS, AND JOHN B. NEIL, OF NEW YORK, N. Y., ASSIGNEES TO THE BIGELOW CARPET COMPANY, OF CLINTON, MASSACHUSETTS.

DESIGN FOR A CARPET.

SPECIFICATION forming part of Design No. 12,435, dated August 30, 1881.

Application filed August 6, 1881. Term of patent 3½ years.

To all whom it may concern:

Be it known that we, HUGH CHRISTIE, of Boston, in the county of Suffolk and State of Massachusetts, and JOHN B. NEIL, of New York, in the county and State of New York, have invented a new and original Design for Carpets, of which the following is a specification.

This invention relates to a new and original design for carpets and similar fabrics; and it consists in the novel grouping and configuration of figures hereinafter more fully shown and described.

The accompanying photograph illustrates a face view of a carpet bearing our new design.

The stripe B is composed of the band r, containing a series of parallel bars running across it; also, the band n, ornamented with a pattern resembling a close-set picket-fence, each 20 picket containing a rectangular figure near its end, and with a row of ornamental figures set between the points of the pickets. The stripe B also contains the band k, ornamented with diagonally-crossed lines; also, the band m, 25 containing a series of figures projecting from the edges toward the center, and resembling the stalactites and stalagmites in a cave; also, the band j, containing a series of rectangles set edgewise, and having projecting from one 30 side a sort of fringe composed of leaf-like projections alternating with projecting bars.

The stripe A contains the figure C, composed of a bunch of flowers, e, a portion of which, f, projects over a figure, b, resembling a spider's web, while another part—a projecting spray, g—extends over the figure c, resembling a checkerboard, and between it and the figure d a rectangular figure ornamented with a tooth-like pattern. The figure D in the stripe A is composed of a bunch of rose-like flowers, h, from 40 which extends the figure i—a bunch of flowers with projecting leaves. These figures C and D are repeated alternately to make up the stripe A. The stripe a contains an ornamentation of lines crossing each other diagonally. 45

We claim—

1. The design for carpets, consisting of the figures c and d, substantially as shown. 50
2. The design for carpets, consisting of the figures e, f, and g, substantially as shown. 55
3. The design for carpets, consisting of the figure b, substantially as shown.
4. The design for carpets, consisting of the figures f, e, g, c, and d.
5. The design for carpets, consisting of the group C, containing figures b, e, f, c, g, and d, substantially as shown.
6. The design for carpets, consisting of the group D, containing figures h and i, substantially as shown. 60
7. The design for carpets, consisting of the stripe A, containing figures b, f, e, g, c, d, h, and i, substantially as shown.
8. The design for carpets, consisting of the stripe a, stripe C, containing figures b, f, e, g, 65 c, d, h, and i, and stripe B, containing figures j, m, k, n, and r, substantially as shown.
